MANGLING ROLLER

Paul Scheibe, Cologne-on-the-Rhine,
GermanyApplication November 18, 1932, Serial No.
643,300, and in Germany November 24, 1931

11 Claims. (Cl. 68—9)

This invention relates to a mangling roller having a shell or covering consisting of yielding members arranged side by side, each of these members being pressed outwardly, for instance by means of a spring located below it; said roller is, besides, provided at its circumference with circumferential chambers or grooves formed by spaced rings and containing said yielding members which are laterally guided by said rings.

10 The hot mangling machines that have become known up to now have rollers with a hard surface, these rollers being covered with a fabric consisting of nettle, asbestos, molton, or the like, and the object of this soft covering is to permit the mangling also of pieces of linen or the like having, for instance, thick seams or monograms or flat buttons forming protuberances, these projecting parts being pressed down into the covering while the pieces of linen etc. are being mangled. That is possible, however, only so long as the covering is new and elastic, but it becomes soon hard and unyielding by reason of the continuous pressure to which it is subjected, also under the action of the warm and moist air, so that said projecting parts of the linen etc. are no more pressed down into the covering, but the pieces of linen etc. are damaged by them.

30 Of late mangling machines have become known, the rollers of which are more yieldable to the pressure caused by the seams etc. and remain also longer in proper operative state as regards their greater yieldingness of the covering. This latter consists of, or is provided with, plate springs or equivalent members, for instance metallic brushes, which are covered with a layer of cloth or the like that encompasses the springs etc. so tightly that the respective elastic members are subjected to a correspondingly strong tension 40 which, in turn, keeps the covering or cloth tight and gives it the certain so-to-say hardness as requisite for the work to be done.

But the fact that the metallic brushes or the plate springs etc. are depressed or compressed by the cloth surrounding and covering them already prior to the mangling constitutes a drawback. The covering is subjected to strong tensile strain by the depressed or compressed springs or brushes and this strain can be, and is often times, so much increased by the seams or other protuberances, as the case may be, that the covering tears. Furthermore, those rollers lack a tangential coupling of the elastic shell formed by the yielding members with the inner body or core of the roller.

The mangling effect attained with the mangling rollers dealt with in the preceding two paragraphs is insufficient because the pressure points are by far too small so that the covering cloth is destroyed after a short time. If the yielding shell is provided with, or consists of, plate springs, the elasticity of the various springs is different, in consequence whereof the elasticity of those springs which are subjected to a stronger strain is detrimentally affected.

Furthermore, with those rollers, or their yielding shell respectively, the elastic members, especially the springs, are not laterally guided and they can, therefore, give way to all sides whereby not only their manner of action, but also their security of service is rendered questionable.

Finally, the extent of movement of the elastic members of the shell of said known mangling rollers is not bounded by abutment members. If the protuberances of the pieces of linen worked with them are comparatively high, the elastic members are too strongly bent and, perhaps, pressed upon the rigid body or core of the roller so that they are likely to be damaged or even broken.

My improved mangling roller is free from the above-mentioned drawbacks of the known mangling rollers and is illustrated diagrammatically and by way of example on the accompanying drawing on which Figure 1 is an axial section through a mangling roller designed according to this invention. Figure 2 is a transverse section through the roller, together with an end-view of the tray or trough in which the roller is located. Figure 3 shows an end-view of, as well as a transverse section through, one of the above-mentioned rings between which the elastic members are located and by which they are laterally guided. Figure 4 shows a front-view, a side-view and a plan of one of the springs used in this constructional form of the mangling roller. Figure 5 shows a side-view of, a transverse section through (in the line A—B of the side-view), and a plan of one of certain plate-like members located above said springs and being subjected to the pressure of the same. Figure 6 is a transverse section through a portion of the hollow roller body, the elastic shell (composed of said plates and said springs), the cloth covering of the same, and the tray or trough, this figure being drawn to a greatly enlarged scale relatively to Figs. 1—5. Figure 7 is a front-view of a portion of the elastic shell, the scale being the same as in Fig. 6. Figure 8 is a view similar to Fig. 6 and shows a modification. Figure 9 is a plan of

the parts shown in Fig. 8, and Figure 10 is a perspective view of a detail more fully dealt with hereinafter.

On the drawing, *a* (Figs. 1, 2 and 6) denotes the hollow body or core of the roller which is provided with perforations *h* through which the damp may be sucked away from the moist linen. The body *a* is surrounded with a large number of rings *c* (Figs. 6 and 7) in which are supported a big number of axles *d* extending parallel to the axis of the roller. On these axles are supported springs *b* (Fig. 4) and plates *e* (Fig. 5) in staggered arrangement, as shown in Fig. 7. The plates *e* which are laterally guided by said rings *c* constitute so-to-say double-armed levers, one arm forming the plate proper and the other arm forming an abutment lug *e'* (Fig. 5) which bears upon the roller body, as shown in Fig. 6. The plates *e* are held lifted by the springs *b*, but can be lifted only so much as is permitted by said abutment lugs *e'*.

g (Fig. 6) is the covering which consists of cloth or the like. The cloth is not subjected to the pressure of the springs, that is to say, it is not subjected to tensile strain. The cloth is just kept smooth, without folds in it. It covers the plates *e*, the length of which is such that they overlap one another in the circumferential direction of the roller, as appears from Fig. 7. For this purpose the plates are slightly curved (Fig. 5) and the axles *d* are sufficiently far remote from the roller body that the lugs *e'* can be turned in the direction to the axles when the plates *e* are depressed. Each plate is subjected to the pressure of the spring located opposite its concave side, on the respective adjacent axle. It will be obvious that each spring can give way when the covering portion above it is subjected to a pressure exerted, for instance, by a seam or a monogram or a flat button etc. The pieces of linen to be mangled are led through between the roller and the trough which latter is hollow and heated, as known with mangling machines. While the pieces of linen pass through between the roller and the trough they are subjected to the mangling pressure, as known, as the pressure is exerted by the springs *b* in that they are compelled to give way under the resistance of the pieces of linen present in the trough, the pieces of linen are pressed against the trough by said springs, any one of which is able to give way if a seam or other protuberance should arrive above it. There arises then in the respective portion of the covering cloth a certain cavity, as shown in Fig. 6, that cavity disappearing instantly when it has been moved past the end of the path in the trough.

As the upper surface of the plates *e* is perfectly smooth, there is only a very slight friction between them and the cloth which is, therefore, excellently preserved.

The elastic shell of the roller, as formed by the plates *e* and the springs *d* does not vibrate, in that the plates are rigid and do not show elasticity in tangential direction owing to their configuration and arrangement, as described. There is also no rebounding, in that this is prevented by the abutment lugs *e'*. The size of the plates *e* and their number is such that they present in their entirety a uniform and highly elastic, also uniformly elastic, surface which constitutes an excellent supporting surface for the cloth *g*.

If a particularly high protuberance, for instance a somewhat thick button, should find access between the mangling roller and the

trough, the elastic and yielding members *b* and *e* concerned will nevertheless not be damaged, in that they will be protected by the adjacent rings *c*.

In the modification shown in Figs. 8-10 there are no such lever-like members as *e e'* but instead thereof members *i* (Fig. 10) resembling each an inverted U are provided, these members being inserted between the rings *c* (which are practically the same as in the first described constructional form) in the manner shown in Fig. 9. Instead of the axles *d* of Figs. 6 and 7 axles *j* are provided which also extend transversely through said rings, or parallel to the axis of the roller respectively, and bear pairs of helical springs shaped and arranged in the manner shown in Figs. 8 and 9. Each pair of said springs holds one of said yielding members *i* in operative position and permits the respective member to give way, if necessary. One end (*l'*) of each spring bears upon the roller body, upon which it can slide, and the other end (*l''*) is bent around the appertaining axle *j*. The axles *j* are provided with tubular spacing member *k* for the rings *c*. The yielding members *i* can be moved inwardly counter to the pressure of the springs *l*, in the direction to the axles *j*, but moving them inwardly too far is prevented by the rings *c*. Each leg of each of the inverted members *i* is provided with a slot *i'* for the passage of the spring ends *l''* and the top has lateral ledge-like projections *i''* that contact with the adjacent two rings *c* when the member *i* has been depressed into its lowermost position. In Fig. 8 the two members *i* at the left-hand end of the figure are shown in their depressed state, that is to say, they are here depressed so much that their ledges *i''* bear upon the adjacent rings *c*. The other members *i* are in their normal position.

This constructional form is particularly suited to accommodate the operative surface of the mangling roller to the varying pressures arising while the pieces of linen are led through the machine. A particular advantage is, besides this that the supporting surface, as presented by the members *i*, is the largest possible which is very useful for the covering cloth i. e. for the length of its lifetime. Other advantages of this constructional form over that shown in Figs. 1-7 reside therein that the entire construction is considerably simpler, and the roller can be turned in both directions.

Finally, I wish it to be understood that my invention is not limited to all the details shown in the drawing merely by way of example. Many departures in the details are possible without constituting also a departure of the invention.

I claim:

1. A mangling roller, comprising, in combination with the body of the roller, spaced rings encompassing said body on the entire length of the same; individually compressible members having a flat upper surface and being arranged between said rings and following one another around the entire circumference of the body; springs located below said compressible members and holding them normally in proper operative position; and a covering around all said compressible members.

2. A mangling roller, comprising, in combination with the body of the roller, spaced rings encompassing said body on the entire length of the same; individually compressible members having a flat upper surface and being arranged between said rings and laterally guided by them; springs located below said compressible members and holding them normally in proper operative

- position; and a covering around all said depressible members.
3. A mangling roller, comprising in combination with the body of the roller, a yielding shell composed of circumferential rows of depressible members having each a flat surface; axles located between said body and said shell and extending parallel to the axis of the roller and supporting said depressible members; springs arranged below the depressible members and holding them normally in working position; and a covering surrounding all the said depressible members.
4. A mangling roller, comprising in combination with the body of the roller, a yielding shell composed of circumferential rows of depressible members having each a flat surface; axles located between said body and said shell and extending parallel to the axis of the roller and supporting said depressible members; means supporting said axles and being so designed as to be adapted to guide the depressible members at their sides; springs arranged below the depressible members and holding them normally in working position; and a covering surrounding all the said depressible members.
5. A mangling roller, comprising, in combination with the body of the roller, spaced rings encompassing said body along the entire length of the same; axles supported by said rings and being arranged around the entire circumference of the said body; individually depressible members located above said axles and being movable relatively to the same; springs engaging with one end said depressible members and bearing with the other end upon the said body so as to hold the depressible members in proper operative position; and a covering on all said depressible members.
6. A mangling roller, comprising in combination with the body of the roller, axles extending outside said body parallel to the axis of the roller; depressible members supported on said axles and forming each a double-armed lever, one arm of which bears upon the said roller and the other arm of which is plate-shaped and directed counter to the first-mentioned arm; springs also supported on the said axles and tending continuously to move said plate-shaped lever arms outwardly; and a covering enclosing all these lever arms.
7. A mangling roller, comprising, in combination with the body of the roller, axles surrounding said body parallel to the axis thereof; means supporting said axles on said body; double-armed levers supported on said axles and forming at one end a smooth plate and at the other end an abutment lug, the arrangement being such that the lugs bear on the said body when said plates are in proper operative position; helical springs also arranged upon the said axles below the said plates and holding them in operative depressible position, and a covering surrounding the entire yielding shell formed by the said depressible lever plates, substantially as set forth.
8. A mangling roller, comprising, in combination with the body of the same, spaced rings affixed to the body along the entire length of the same; depressible members located between said rings and being guided by them and forming each an inverted U, the legs of the consecutive U's following one another around the circumference of the roller body; axles extending transversely through said rings and between the legs of the U's; pairs of helical springs having each one of its ends bearing upon one of the depressible U's and encompassing with its other end an adjacent axle so as to hold the appertaining depressible member in proper operative position; and an envelope around all said depressible members, substantially as set forth.
9. A mangling roller, comprising in combination with the body of the roller, yieldably supported members which are U-shaped in section and surround without gaps the entire circumferential surface of said body; equally spaced rings distributed over the entire length of the body and being firmly connected therewith and guiding said members laterally and limiting the inward movement of the same; springs located in said yielding members between the legs of the same and pressing the said members upwardly so as to hold them in working position; and a covering surrounding all the said depressible members.
10. A mangling roller, comprising, in combination with the body of the roller, spaced rings attached to the body on the entire length of the same; depressible member representing each an inverted U having a slot in each leg and having projecting abutment ledges at its top, the arrangement being such that said ledges can bear upon said rings; pairs of helical springs, one pair in each of said depressible members between the legs of the same, the neighbouring ends of the springs forming one pair extending through one of said slots and bearing on the said body; axles extending transversely through said rings and through between the legs of the inverted members, the other ends of said springs encompassing the adjacent portion of the adjacent axle and both ends holding the individual depressible member in its proper operative position; and a common outer covering for all depressible members, substantially as set forth.
11. A mangling roller, comprising, in combination with the body of the roller, individually depressible members, each of which is U-shaped in section and has its legs directed towards the axis of the roller; equally spaced rings surrounding said body and holding said depressible members between them, guiding them laterally and limiting their stroke in inward direction; axles located between the working faces of the depressible members and the roller body, moderately remote from this latter; springs located between the legs of the U-shaped depressible members and pressing these members upwardly so as to hold them in working position; and a covering surrounding all the said depressible members.

PAUL SCHEIBE. 140
